[57] CLAIM

The ornamental design for an oral inhaler, as shown and described.

DESCRIPTION

FIG. 1 is a perspective view of an oral inhaler showing our new design;

FIG. 2 is a top plan view thereof, the bottom plan view being identical thereto;

FIG. 3 is a front elevational view thereof, the rear elevational view being identical thereto;

FIG. 4 is an end elevational view thereof, the opposite end elevational view being identical thereto;

FIG. 5 is a top perspective view thereof in open position;

FIG. 6 is a top plan view thereof;

FIG. 7 is a front elevational view thereof;

FIG. 8 is a bottom perspective view thereof;

FIG. 9 is a bottom plan view thereof; and,

FIG. 10 is a rear elevational view thereof.
